US0D1018133S

(12) **United States Design Patent** (10) Patent No.: **US D1,018,133 S**
(45) Date of Patent: ** Mar. 19, 2024

(54) **PILLOW**

(71) Applicant: **Jingang Yang**, Guangan (CN)

(72) Inventor: **Jingang Yang**, Guangan (CN)

(**) Term: **15 Years**

(21) Appl. No.: **29/821,744**

(22) Filed: **Jan. 2, 2022**

(51) LOC (14) Cl. **06-09**

(52) U.S. Cl.

USPC **D6/601**

Primary Examiner — Sanjeev Paul

(74) Attorney, Agent, or Firm — ScienBiziP, P.C.

(57) **CLAIM**

The ornamental design for a pillow, as shown and described.

DESCRIPTION

FIG. 1 is a front, right and bottom perspective view of a pillow, showing my design.

FIG. 2 is a front, left and top perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof; and,

FIG. 8 is a bottom plan view thereof.

1 Claim, 8 Drawing Sheets
